Primary Examiner — Sheryl Lane(74) Attorney, Agent, or Firm — Inventa Capital PLC(57) CLAIM

I claim the ornamental design for a trimmer head, as shown and described.

DESCRIPTION

FIG. 1 is a bottom view of a trimmer head of the present invention;

FIG. 2 is a top view of the trimmer head of the present invention;

FIG. 3 is a side view of the trimmer head of the present invention;

FIG. 4 is an alternative side view of the trimmer head of the present invention;

FIG. 5 is a bottom isometric view of the trimmer head of the present invention; and,

FIG. 6 is a perspective view of the trimmer head of the present invention.

The portions of the article such as a trimmer head, shown in broken lines form no part of the claimed design.
